UNITED STATES PATENT OFFICE.

EARNEST LEE ROTTMAN, OF SALT LAKE CITY, UTAH.

TYPE-WRITER ATTACHMENT.

1,100,916.

Specification of Letters Patent.

Patented June 23, 1914.

Application filed July 12, 1913. Serial No. 778,810.

To all whom it may concern:

Be it known that I, EARNEST LEE ROTTMAN, a citizen of the United States, and a resident of Salt Lake City and Salt Lake 5 county, Utah, have invented a new and useful Type-Writer Attachment, of which the following is a specification.

My invention relates to a holder to be applied to a desk to secure the typewriter in position and is especially desirable for attaching to a tipping table inside of a typewriter desk to hold the typewriter in position. When metallic fasteners are used for this purpose the sound travels down them 15 from the machine and the table acts as a sounding board, making it very unpleasant for the operator. To obviate this sounding board feature, I do not fasten the typewriter rigidly to the board or table but permit some play between the fastener and the typewriter.

By the use of my invention all the disagreeable sounding board feature is removed. I accomplish this by the invention 20 illustrated in the accompanying drawings, in which—

Figure 1 is a perspective view of the entire device; Fig. 2 is a plan, Fig. 3 is a cross section, Fig. 4 is a front elevation, Fig. 5 30 is a section showing attachment to the typewriter and Figs. 6 and 7 are plans showing variations in the shape to fit various makes of typewriters.

Similar numerals refer to similar parts 35 throughout the several views.

1, 1 are screws passing through holes in the arms 2, 2 by which the device is attached to the table or desk.

3, 3 are the ends and 4 the top.

40 5, 5, and 6, 6 are felt pads.

In attaching the device the back of the typewriter is lifted up and the bar inserted behind the back 8 of the typewriter. The device is then attached to the desk by means 45 of the screws 1, 1 being driven into the wood. When the back of the tipping table inside the desk is tipped back and downward it is prevented slipping back or tipping backward by the back of the device and the bar 7.

In order to accommodate the post found 50 on some makes of machines I cut out the portion 8' shown in Fig. 7 or the portion 9, and for similar reasons the portion 10 in Fig. 6 may be cut out.

Having thus described my invention what 55 I claim as new and desire to secure by Letters Patent is—

1. As a new article of manufacture a casting substantially rectangular in form, having a closed back, top, bottom and ends, 60 a recessed front with offset castings at the bottom forming supporting arms projecting forwardly and having pads at the ends, top and back.

2. A casting for use for holding a type- 65 writer on a desk, substantially rectangular in shape, having a top, bottom, back and ends, lugs at the bottom adapted for insertion behind the back of the lower frame of a typewriter and having offset arms 70 projecting forwardly by means of which same may be braced when attached to a typewriter desk and means for attaching same to a desk.

3. As a new article of manufacture, a 75 typewriter fastening attachment, substantially rectangular in shape having closed back, top, bottom and ends and having a recessed front, with lugs projecting upward from the bottom at the front adapted to insert behind the back frame of the typewriter, and said article adapted to be secured to a desk and retain the typewriter in position.

4. As a new article of manufacture a 85 casting substantially rectangular in shape having a closed bottom, top, back and ends, a recessed front, lugs projecting upward from the front of the bottom, means for padding between said casting and a typewriter held in position by same and means for attaching said casting to a desk.

5. The herein described typewriter fastener attachment, comprising a substantially rectangular body, with offset supporting braces projecting forwardly from the bottom and ends, a recessed front, lugs projecting upwardly from the bottom near each

end, adapted to be inserted behind the back-frame of a typewriter means to prevent the marring of the typewriter to which same may be attached and means for securing said attachment to a typewriter desk, all substantially as above described.

In witness whereof I have hereunto set

my hand in the presence of two subscribing witnesses.

EARNEST LEE ROTTMAN.

Witnesses:

F. J. VINCENT,
J. C. EDGAR.
